TREATMENT OF HYDROCARBON OILS

Jacque C. Morrell and Gustav Egloff, Chicago,
Ill., assignors, by mesne assignments, to Uni-
versal Oil Products Company, Chicago, Ill., a
corporation of Delaware

No Drawing. Application December 19, 1931,
Serial No. 582,156. Renewed April 5, 1934

4 Claims. (Cl. 44—9)

This invention relates to the treatment of hydrocarbon oils and refers more particularly to the treatment of low boiling distillates produced in the cracking of heavier higher boiling fractions.

5 More specifically the invention has reference to a process for treating hydrocarbon mixtures undergoing decomposition and conversion reactions or the lower boiling vaporous products of these reactions to produce substantial amounts of compounds which add materially to the anti-knock value of the gasoline finally produced from the process.

While the cracking process as at present generally practiced in the petroleum industry tends to 15 the production of gasolines having anti-knock characteristics superior to those possessed by corresponding gasoline fractions produced by the straight run distillation of crude petroleums, it may frequently happen that the production of a 20 cracked gasoline of a knock rating rendering it saleable as a premium motor fuel may entail the use of relatively severe cracking conditions with attendant increased losses in fixed gases and coke and a decrease in the overall yield of the desired 25 product. In the majority of cases for any given stock charged to the cracking process there exists an optimum set of conditions for producing a maximum yield of gasoline of good anti-knock 30 value, the use of more severe conditions, while they may produce gasoline boiling range fractions closely approximating a mixture of aromatic hydrocarbons in composition, producing not only excessive gas losses but a very material lowering in 35 yield of gasoline so that in this respect it may be stated that the production of increased yields of anti-knock gasoline by the cracking process is limited by economic considerations.

The present invention has as one of its objects 40 provision of a process by which the economic disadvantages of producing high anti-knock value gasoline by cracking may be offset by the production concurrently in the cracking process of compounds having a specially high anti-knock value so that the product of the operation considered as 45 a whole is of the high quality desired and the necessary yields are maintained.

In one specific embodiment the invention comprises treating cracked hydrocarbon vapors with 50 halogens to produce halogen derivatives and further treating with ammonia in the presence of catalysts to produce amines to increase the anti-knock value of gasoline produced from the vapors.

The halogenation of cracked hydrocarbon vapors of approximate gasoline boiling point range 55

will follow a course depending upon the chemical composition of the vapors, the temperature and pressure of treatment and the presence of catalytic material, as well as the amount of halogen and the particular halogen used. Since such vapor mixtures include representatives of the principal hydrocarbon groups, that is, paraffins, olefins, naphthenes and aromatics in varying proportions, the ease of halogenation will depend to some extent upon the percentage of the unsaturated compounds present. For example, in cracked vapor mixtures containing relatively high percentages of olefins, the addition of halogen may proceed with great rapidity independent of catalytic influences and light and electrical effects. When the vapors contain larger percentages of saturated compounds of the straight chain and cyclic series, sufficient halogenation may involve the use of catalysts such as iron, aluminum, zinc, etc., or their halides. The degree of halogenation which it is best to employ in any particular case will depend upon the type of amines which are produced from the halogenated derivatives in the succeeding treatment with ammonia so that the selection of exact quantities of reagents and conditions of operation will be usually best determined by trial runs. While the individual reactions occurring between the hydrocarbons and the treating reagents are necessarily complicated owing to the great variety of hydrocarbon compounds present in the original mixture, it is possible to represent the net result by equations such as the following:

in which R' represents an unsaturated hydrocarbon having one double bond between carbon atoms and R''H represents a saturated hydrocarbon. It will be seen in the first equation that a molecule of chlorine has added directly with saturation of the double bond while in the second equation that the chlorine molecule has been split with one atom of chlorine adding to the hydrocarbon radical and the other joining with an atom of hydrogen. The succeeding reactions resulting when the halogen derivatives are treated with ammonia in the presence of suitable catalysts may be shown as follows:

Numerous metallic catalysts may be employed such as the heavy metals, iron, nickel, cobalt, zinc, cadmium, copper, mercury, manganese, chromium, vanadium, etc., and their oxides and

salts, copper salts such as copper sulfate or copper chloride being specially adaptable. In the selection of a particular catalyst for any given set of conditions the operator will be best guided by experience though it may be stated that the copper compounds mentioned have given uniformly good results in a large number of cases. Similarly it may be found advantageous to utilize the catalysts mixed with or supported upon relatively inert spacing material to insure maximum surface action.

Several alternative methods of operation are possible and are comprised within the scope of the invention. As a general rule, the conditions under which the general reactions are brought about correspond to those of cracked vapors undergoing fractionation under super-atmospheric pressure following the reaction zone of a cracking process, these conditions involving temperatures of from approximately 300 to 600° F. and pressures in the approximate range of 100 to 400 pounds per square inch. According to one method of operation the vapors entering a primary fractionator or separator may receive increments respectively of halogen such as, for example chlorine and at approximately the same point the proper amount of ammonia, the vapor mixture then being passed over or through catalytic material of suitable character. Preferably the vapors are subsequently fractionated to produce gasoline of desired boiling point range containing the amines produced by the reaction above described and refluxes which may be returned to the reaction zone of the cracking process for further conversion.

The relative effect on the anti-knock value of gasoline of amines of the alkyl and aryl groups respectively is indicated by the following table which shows part of the figures given in the International Critical Tables, vol. 2, p. 163.

Relative effects of some compounds of nitrogen for suppressing detonation in engines

Aniline in concentrations up to 3% of the fuel by volume taken as standard of effects. All measurements made with bouncing pin apparatus, using kerosene as fuel (4). The values given below are, (a) amount of grams required to give an "anti-knock" effect equivalent to 1 g. of aniline, and (b) reciprocal of the number of moles, required to give an "anti-knock" effect equivalent to 1 mol. of aniline. Negative values are marked (—).

50	Compound	Formula	(a) Wt. for given effect	(b) Rel. mol. effectiveness
55	Aniline	$C_6H_5NH_2$	1	1
	Cumidine	$(CH_3)_2CH_2NH_2$	0.96	1.51
	Monomethylaniline	$C_6H_5NHCH_3$	0.83	1.4
	Toluidine	$C_6H_4CH_3NH_2$	0.94*	1.22*
	Ethylaminobenzene	$C_6H_5CH_2NH_2$	1.14	1.14
	Methyl-o-toluidine	$(CH_3)_2CH_2NH_2$	1.15	1.13
	Diethylamine	$(C_2H_5)_2NH$	1.50	0.495
	Diethylaniline	$C_6H_5N(C_2H_5)_2$	6.7	0.24
60	Dimethylaniline	$C_6H_5N(CH_3)_2$	6.2	0.21
	Ethylamine	$C_2H_5NH_2$	2.4	0.20
	Triethylamine	$(C_2H_5)_3N$	7.06	0.14

*Average of o-, m-, and p-values.

Of the halogens chlorine, bromine, iodine and fluorine which may be employed alone or in admixture for inducing the desired reaction for the formation of amines, chlorine is by far the most readily adaptable of the group being generally available and at the same time sufficiently reactive to insure the necessary efficiency in the process. Fluorine except in minor admixture will naturally be ruled out on account of its high cost, violent action and corrosive tendencies. It may at times be distinctly advantageous to introduce minor amounts of bromine or iodine with

in the limits of economy, such additions being frequently productive of increased reaction velocities.

In addition to the production of amines which add to the anti-knock value of the gasoline, other treating effects may be produced incidental to the use of certain catalytic mixtures, particularly the compounds of copper which have given good results. For example, cracked vapors may be desulphurized to a considerable extent within the capacity of the metallic contact mass either to the extent of merely sweetening the vapors by conversion of mercaptans to disulphides or further desulphurizing action may occur. The extent of these reactions will depend upon the chemical character of the cracked vapors being treated, the relative amounts of reagents used and other conditions of operation.

The process of the invention may be used as a single treatment on cracked vapors or in combination with preceding, or succeeding treatments for producing as an overall result a finished product of desired characteristics. For example, the vapors may be treated by special desulphurizing and/or polymerizing steps prior to the introduction of the reactants for the production of amines and still further vapor phase treatments, suitable settling periods or filtering by inert or adsorbent materials may follow. In the majority of instances a final rectification to produce an end point gasoline is preferable. Furthermore, the condensed product may require a light final washing to remove traces of reaction products.

As an example of a treatment which may be conducted according to the process of the invention and the results obtainable therefrom, the cracked vapors of approximate gasoline boiling point range coming from the fractionator of a cracking process operating on Mid-Continent residuum may be considered. Such vapors may be evolved from the fractionator under a pressure of approximately 225 pounds per square inch and a temperature of 525° F. Chlorine may be injected into these vapors at the rate of about 4 pounds per barrel of final distillate along with approximately 2 pounds of ammonia, injected either in concentrated aqueous solution or as the dry gas, the vapors then being passed through a treating chamber containing finely divided copper to catalyze the reactions for the production of amines, then to settling and filtering chambers and finally to a fractionator in which the desired high anti-knock gasoline is produced as an overhead fraction. The gasoline produced by fractionating and contacting these vapors with solid adsorbent materials without the use of chlorine and ammonia upon the vapors according to the process of the invention may have the properties shown in the "untreated" column following, while gasoline produced by applying the process of the invention may have the properties shown in the "treated" column.

	Untreated	Treated	65
Octane number	62	70	
Color, Saybolt	11	30	
Gum content by copper dish	20	20 mg.	
Sulfur content	0.31	0.08	
Color stability or loss in Saybolt degrees in the four-hour sunlight test	10	4	70

The yield of gasoline in both cases may be approximately 60% of the residuum processed, with the maximum cracking temperature employed 930° F. with a pressure of 250 pounds per square

inch. To produce the octane number by straight cracking and fractionation without the use of special vapor phase treatment according to the process of the invention may entail a reduction 5 in yield to approximately 52%, which is a serious consideration in commercial work and might render the process uneconomical. Thus the application of the present invention is shown to have definite commercial value.

10 10 The foregoing general description of the process of the invention and the example of the results obtainable by one operation thereof is sufficient to enable one skilled in the art to recognize its value but since the exact type of operation may 15 be considerably varied and the amount of reagents also varied in the treatment of different stocks, the process as disclosed is not to be construed in any way as a limitation upon the broad scope of the invention.

20 20 We claim as our invention:

1. In the cracking of hydrocarbon oils by heat and pressure wherein cracked vapors containing gasoline are separated from residuum, the method which comprises adding a halogen and ammonia 25 to the cracked gasoline vapors after their separation from the residuum, interacting the halogen, ammonia and a part of the vapors in a vapor zone of the cracking process where the vapors are at a temperature of from 300 to 600° F. to form 30 amino derivatives, and condensing and collecting the gasoline vapors containing the amino derivatives thus formed.

2. In the cracking of hydrocarbon oils by heat and pressure wherein cracked vapors containing gasoline are separated from residuum, the method which comprises adding a halogen and ammonia 35

to the cracked gasoline vapors after their separation from the residuum, interacting the halogen, ammonia and a part of the vapors in the presence of a catalyst having a refining action on the vapors and in a vapor zone of the cracking process where the vapors are at a temperature of from 300 to 600° F. to form amino derivatives, and condensing and collecting the gasoline vapors containing the amino derivatives thus formed. 5

3. In the cracking of hydrocarbon oils by heat and pressure wherein cracked vapors containing gasoline are separated from residuum, the method which comprises adding chlorine and ammonia to the cracked gasoline vapors after their separation from the residuum, interacting the chlorine, 15 ammonia and a part of the vapors in a vapor zone of the cracking process where the vapors are at a temperature of from 300 to 600° F. to form amino derivatives, and condensing and collecting the gasoline vapors containing the amino derivatives 20 thus formed.

4. In the cracking of hydrocarbon oils by heat and pressure wherein cracked vapors containing gasoline are separated from residuum, the method which comprises adding chlorine and ammonia 25 to the cracked gasoline vapors after their separation from the residuum, interacting the chlorine, ammonia and a part of the vapors in the presence of a catalyst having a refining action on the vapors and in a vapor zone of the cracking process 30 where the vapors are at a temperature of from 300 to 600° F. to form amino derivatives, and condensing and collecting the gasoline vapors containing the amino derivatives thus formed. 35
